UNITED STATES PATENT OFFICE.

THOMAS D. CASHIN, OF MONTROSE, PENNSYLVANIA.

SEESAW.

SPECIFICATION forming part of Letters Patent No. 357,577, dated February 15, 1887.

Application filed August 21, 1886. Serial No. 211,468. (No model.)

To all whom it may concern:

Be it known that I, THOMAS D. CASHIN, a citizen of the United States, residing at Montrose, in the county of Susquehanna and State of Pennsylvania, have invented certain new and useful Improvements in Seesaws; and I do hereby declare the following to be a full, clear, and exact description of the invention, such as will enable others skilled in the art to which it appertains to make and use the same.

My invention consists of an improved seesaw, having the features and constructed in the manner hereinafter described and claimed. It is illustrated in the accompanying drawings, in which—

Figure 1 is an elevation in perspective. Fig. 2 is a longitudinal view, in section, of the fulcrum-piece and the arms attached thereto; Fig. 3, a detail view of the fulcrum-piece; Fig. 4, a detail of one of the arms, and Figs. 5 and 6 views, partly in section, of modifications.

In the drawings, A is a central fulcrum-piece, which is there shown circular in form, but which may be square or of other suitable form, and is provided with sockets *a* of an oblong shape.

B and B' are the arms of the seesaw, curved from near their center to their inner ends, and beveled at such ends. These ends of the arms are placed in the sockets *a*, and one or both of them may be permanently secured to the fulcrum by means of pins *d*, or other fastenings, passed through the section *e* of the fulcrum, between the sockets *a*, and through the ends of the arms, as shown in Fig. 2; but the arms can be attached to the fulcrum for use by simply inserting their beveled ends in the sockets without additional securing. The arms are curved, as shown, so that when detached from the fulcrum they may be placed together "spoon fashion," thus occupying but little space indoors when not in use, and to increase convenience of packing into a small

compass for purposes of transportation. If desired, one of the arms may be permanently secured to the fulcrum, and the detachable arm can be then packed just as well against the other. If also desired, the arms B B' may be made straight.

E E are cords for connecting and supporting the arms B B'. Instead of cords other suitable arms, rigid or flexible, may be employed.

In the modification shown in Figs. 5 and 6 the fulcrum is provided with but a single socket, and the arms are hinged together. To one side of the socket *a* is made fast the arm B, the inner end of which is beveled and provided with the holes *b' b'*, with which hooks *c* on the end of the detachable arm B' are made to engage.

The arms B B' may be provided with cross-pieces at their outer ends for supports for the riders.

Having thus described my invention, what I claim is—

1. A seesaw formed of two curved arms, in combination with a central fulcrum, to which the inner ends of said arms are independently attached, substantially as described.

2. A seesaw comprising, in combination, the central fulcrum, which rests and rocks directly on the ground or other surface upon which it rests, the separate and independent arms, and the supports connecting the arms, substantially as described.

3. In a seesaw, the combination of the curved arms beveled at their inner ends, and a central fulcrum having sockets for the reception of said arms, substantially as described.

In testimony whereof I affix my signature in presence of two witnesses,

THOMAS D. CASHIN.
